UNITED STATES PATENT OFFICE.

ELLIS S. HELWITZ, OF BROOKLYN, NEW YORK.

DESIGN FOR A HEEL-TIP.

51,592.

Specification for Design.

Patented Dec. 18, 1917.

Application filed April 18, 1917. Serial No. 163,093. Term of patent 7 years.

To all whom it may concern:

Be it known that I, ELLIS S. HELWITZ, a subject of George V of Great Britain and Ireland, residing at Brooklyn, in the county of Kings and State of New York, have invented a new, original, and ornamental Design for Heel-Tips, of which the following is a specification, reference being had to the accompanying drawings, forming part thereof.

Fig. 2 is a front elevation,
Fig. 3 is a side elevation, and
Fig. 4 is a bottom plan view.

I claim:

The ornamental design for a heel tip as shown.

ELLIS S. HELWITZ.
